ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,229,445.

Specification of Letters Patent. Patented June 12, 1917.

Application filed February 7, 1916. Serial No. 76,599.

To all whom it may concern:

Be it known that I, ARTHUR J. HALL, a subject of the King of Great Britain, and a resident of Wilkinsburg, in the county of 5 Allegheny and State of Pennsylvania, have invented a new and useful Improvement in Control Apparatus, of which the following is a specification.

My invention relates to control apparatus 10 and especially to operating mechanisms for motor-controlling devices and the like.

The object of my invention is to provide an apparatus of the above-indicated character which shall be relatively simple in construction and effective and reliable in operation, and whereby a movable member, such as a part of a switching device, may receive a predetermined initial movement that is more rapid than the remainder of the operation.

More specifically stated, it is the object of my invention to provide a fluid-pressure-operated mechanism that is normally biased by unbalanced pressure conditions to a predetermined position and that embodies means for reversing the unbalanced action to effect normal movement of the movable member, and also means for permitting a relatively rapid independent movement of 30 the member before the completion of the reversal just mentioned, thereby eliminating a time element which is more or less inherent in the type of apparatus under consideration.

My invention may best be understood by reference to the accompanying drawings, wherein Figure 1 is a diagrammatic view of a control apparatus of the liquid rheostat type that embodies my invention; Fig. 2 is 40 a diagrammatic view of the auxiliary governing circuits for manipulating the operating mechanism that is shown in Fig. 1; Fig. 3 is a diagrammatic view of a control system embodying another application of my invention; and Fig. 4 is a diagrammatic view of the auxiliary circuits for governing the control system that is shown in Fig. 3.

Referring to Fig. 1 of the drawings, the 50 structure shown comprises, in general, a liquid-rheostat apparatus LR and an operating mechanism OM therefor.

The liquid rheostat may be of any familiar type and is here illustrated as comprising a plurality of suitable tanks or ves-

sels 1 and 2 for containing electrolyte during the acceleration of the motors (not shown) that are to be governed; a plurality of sets of electrodes or plates 3 and 4 for the respective tanks 1 and 2; a common reservoir or discharge tank 5; a plurality of suitable inlet passages or pipes 6 and 6^a for the respective tanks 1 and 2; a discharge passage or pipe 7 for the reservoir 5 and a plurality of suitable regulating valves 8 and 9 for adjusting the height of the electrolyte in the tanks 1 and 2, respectively. Inasmuch as the particular type of motor-controlling device is immaterial to my present invention, except in so far as it performs a necessary function in connection therewith, I do not deem it necessary to describe in further detail the liquid rheostat LR. However, for a more extended description of the general type of apparatus that is here 75 shown, reference may be had to my co-pending application, Serial No. 873,919, filed November 25, 1914.

The valves 8 and 9 are respectively provided with suitable operating rods 10 and 11 that extend upwardly through the tanks 1 and 2 and are respectively pivotally associated with horizontally-disposed arms 12 and 13, which are directly associated with the operating mechanism OM in a manner 85 to be described. It will be understood that by the upward movement of the arms 12 and 13, and, consequently, of the regulating valves 8 and 9, the level of the electrolyte in the respective tanks 1 and 2 is gradually 90 raised, in accordance with a familiar practice, to effect motor acceleration.

The operating mechanism OM comprises a suitable cylinder 20 within which a pair of pistons 21 and 22 are adapted to travel; 95 and a plurality of pairs of governing valves, on-1 and on-2, and off-1 and off-2, that are located near the respective ends of the cylinder. A suitable stop member or barrier 21^a is disposed at a predetermined point 100 in the cylinder 20 to engage the inner surface of the piston 21 and prevent further movement thereof in one direction, for a purpose to be set forth later. A rod or stem 23 is secured to the inner side of the piston 21 and is provided with an end portion 24 of a reduced diameter, for a reason that is explained below.

The other piston 22 is provided with a similar rod or stem 25 that is secured to the 110

inner face thereof, and a sleeve member 26 has one end expanded to form a suitable backing portion 27 for the piston 22, and extends upwardly within the cylinder 20, 5 rigidly inclosing the piston rod 25 and loosely surrounding the lower portion of the piston rod 23. One end of a suitable helical spring member 28 incloses the reduced end-portion 24 of the piston rod 23, while the 10 other end of the spring 28 rests upon the inner end of the piston rod 25, whereby normally the spring 28 constitutes the only mechanical connection between the piston rods 23 and 25. The distance between the sleeve 15 26 and the piston 21 corresponds to the distance that the valve members 8 and 9 have to be actuated to raise the electrolyte in the tanks 1 and 2 from the completely discharged level to the "flush-level" wherein 20 the tips of the electrodes 3 and 4 are just immersed.

The sleeve member 26 is provided with a pair of recessed side lugs or projections 29 and 30 within which the ends of operating arms 12 and 13 of the valves 8 and 9 are respectively rigidly mounted.

Each of the "on" valves comprises a suitable actuating coil 35 and a valve member 36 which is suitably biased to a position that 30 normally excludes the access of fluid-pressure from a supply-pipe or passage 37 to the lower end of the cylinder 20. When the actuating coils 35 are energized, fluid-pressure is admitted beneath the piston 22 to 35 effect a movement thereof that is described later.

On the other hand, each of the "off" valves comprises a suitable actuating coil 38 and a valve member 39 which is normally biased to an open position, whereby fluid-pressure is admitted from a suitable source 40 through a pipe or passage 40 to the upper end of the cylinder 20. When the "off" valves have their actuating coils 38 energized, communication between the source of fluid pressure and the upper end of the cylinder 20 is interrupted and fluid pressure is allowed to be released from the upper end of the cylinder. In this manner, the piston 21 is normally biased to engagement with 45 the stop member 21^a, whereas the other piston 22 and the operating members that are associated therewith are normally biased to the position shown in the drawing, by the 50 action of the spring 28.

Assuming that the various parts of the apparatus occupy the respective positions shown, the operation of the structure when a motor is being accelerated may be set forth 55 as follows: Upon the simultaneous energization of the "on" and the "off" coils, as described in connection with Fig. 2, fluid pressure is first admitted to the lower end of the cylinder 20 beneath the piston 22, 60 which is immediately actuated upwardly

against the relatively weak opposition of the spring 28, until the sleeve 26 strikes the piston 21, thereby permitting the relatively rapid rise of the electrolyte level in the tanks 1 and 2 to the positions marked "Flush-level", since the distance between the sleeve and the piston and between the discharge level and flush-level of the rheostats correspond to each other, as previously mentioned. Provided the fluid-pressure has 70 by this time been sufficiently reduced in the upper end of the cylinder 20 by the communication thereof with the atmosphere upon the closure of the "off" valves, then the unbalanced fluid-pressure conditions, 75 which it will be noted are reversed from the normal unbalanced conditions, will operate to effect the further upward movement of the piston rods 23 and 25 and the associated valve-actuating members to all practical intents and purposes as though the pistons 21 and 22 were rigidly connected. Such upward movement of the valves 8 and 9 may 80 be controlled in the manner that is about to be set forth in connection with the governing system of Fig. 2.

When both the "on" and the "off" valve-actuating coils are simultaneously deenergized, unbalanced-pressure conditions revert to the original state, whereby fluid-pressure is admitted to the upper end of the cylinder 95 20 and is exhausted from the lower end thereof. Consequently, the pistons 21 and 22 continue to act as a unitary member until the piston 21 engages the stop member 21^a, whereupon the remainder of the downward movement of the valve-actuating mechanism is effected by the action of the spring 28, which forces the piston 22 and the associated operating members to the position 100 105 that is shown in the drawing.

It will be observed that I have thus provided a movable member and fluid-pressure operating means therefor that is normally biased to a predetermined position, and which comprises an operating cylinder, a plurality of pistons traveling therein and a resilient lost-motion connection that is disposed intermediate the pistons and thus permits a relatively rapid movement of the 110 valve-actuating mechanism to a predetermined point. In other words, the normally unbalanced fluid-pressure conditions in the cylinder 20 are reversed to effect normal upward movement of the valves 8 and 9, and the lost-motion connection permits an initial accentuation of the reversed unbalanced-pressure conditions with respect to the piston 22, and a rapid movement thereof that is independent of the piston 21 is effected. 115 120 125

The advantages of the above-described structure over the prior art may be set forth as follows: In the former operating mechanisms that employ a permanent rigid connection between the pistons, for example, as 130

illustrated in a co-pending application of N. W. Storer and A. J. Hall, Serial No. 724,063, filed Oct. 5, 1912, and assigned to the Westinghouse Electric & Manufacturing Company, a certain time element must elapse before fluid-pressure can be exhausted from one end of the cylinder and thus permit the operation of the pistons by reason of the simultaneous admission of fluid pressure to the other end of the cylinder. Such a time element is undesirable, and various ways of obviating the difficulty have been proposed and which, in general, perform a similar function to that of the apparatus hereinbefore described.

Another advantage over systems heretofore proposed resides in the fact that especially when structures of the type in question have been applied to operate drum controllers through the agency of a rack and pinion connection as is set forth in connection with Fig. 3, it has been necessary to normally dispose the controller drums in their initial operative position, in order that operation of the motors may be effected immediately upon the closure of certain switches and without being delayed by the undesirable time element feature that is mentioned above. On the other hand, if such control drums were placed in their normal "off" position, the cost of supplying some device of the prior art to obviate such time elements would be too expensive; but the economy that is effected by eliminating such time-element-obviating structures is partially offset by the fact that since the control drums occupy their initial operative position, if a supply-circuit-connecting switch should fail to open, then no secondary break in the circuit can be obtained on the drum controller, as is the case when the controllers are returned to their "off" position. Consequently, in order to be perfectly safe under such prior art conditions, it has been necessary to supply an additional supply-circuit-connecting switch, so that two breaks in series are provided.

In accordance with my present invention, only a single supply-circuit connecting switch is necessary, since a secondary break in the circuit is supplied by the drum controller itself in the "off" position; and the relatively low cost of my time-element-obviating device renders its use economical and commercially feasible.

Referring to Fig. 2, the auxiliary governing system shown comprises the actuating coils 35 and 38 of the "on" and "off" valves, respectively; a suitable master controller MC having a plurality of operative positions L, H, R, standing for "lower", "hold" and "raise", respectively; a suitable source of energy, such as a battery B, for the actuating coils, and a plurality of train-line conductors TL of a familiar type for

permitting the use of my invention in connection with the multiple-unit operation of a plurality of cars.

Assuming that it is desired to effect acceleration of the motors (not shown) that are to be governed, the master controller MC may be moved to its final operating position R, whereby one circuit is completed from one terminal of the battery B through conductor 41, control finger 42, contact segment 43 and control finger 44 of the master controller, conductor 45, train-line conductor 46, conductor 47, the parallel-related actuating coils 35 of the "on" valves, conductor 48, train-line conductor 49 and conductor 50 to the negative battery terminal.

A further circuit is simultaneously completed from the contact segment 43 through control finger 51, conductor 52, train-line conductor 53, conductor 54, the parallel-connected actuating coils 38 of the "off" valves, and conductors 55 and 56 to the negative conductor 50.

Since both the "on" and the "off" valve-actuating coils are simultaneously energized, the operating mechanism OM is actuated upwardly to gradually raise the level of the electrolyte in the respective tanks 1 and 2, in the manner hereinbefore mentioned; namely, a relatively rapid movement of the electrolyte to "flush-level" and then a more gradual elevation of the liquid level.

On the other hand, if it is desired to hold the electrolyte at "flush-level," the master controller MC may be initially moved to its second position H, whereby only the actuating coils 35 of the "on" valves are energized. Consequently, the valve-actuating mechanism is immediately moved to the position wherein the sleeve 26 engages the piston 21, when balanced-pressure conditions obtain with respect to the two pistons. A rapid movement to "flush-level" position is thus effected, and no further actuation occurs until the master controller is moved to position R.

To arrest the movement of the operating mechanism at any time during the latter period of operation, it is merely necessary to return the master controller to its intermediate position H, whereby the actuating coils 38 of the "off" valves are deenergized to re-admit fluid-pressure to the upper end of the cylinder 20 and thereby establish balanced-conditions in the cylinder and maintain the operating mechanism stationary. Further acceleration of the motors may, of course, be effected at the will of the operator by again moving the master controller to its position R. To return the operating mechanism to the position that is shown in the drawing, the master controller is moved backwardly to its initial position L or to its "off" position, whereby both the "on" and the "off" valve-actuating coils are deener-

gized and the original unbalanced fluid-pressure conditions obtain in the cylinder 20.

Reference may now be had to Fig. 3 wherein the system shown comprises a plurality of suitable supply-circuit conductors respectively marked "Trolley" and "Ground"; an electric motor having an armature A^1 and a field winding F^1 of the series type; a main-circuit reversing switch RS of any suitable type; a main-circuit switch LS of a familiar electrically-controlled type; an accelerating resistor AR that is adapted to be gradually short-circuited by the operation of a drum-controlling device PK which is actuated by an operating mechanism OM^1 ; and a limit switch L for automatically governing the operation of the mechanism OM^1 in accordance with the current traversing the motor circuit, as hereinafter described.

The controlling device PK is adapted to normally occupy an "off" position and has a plurality of operative positions a' to e' , inclusive, and comprises a main drum-type section MD for governing the main circuits that include the motor and the accelerating resistor, and an auxiliary or interlock drum portion ID for a purpose to be described in connection with Fig. 4.

The operating mechanism OM^1 comprises a shaft 60 upon which the control drum PK is suitably mounted; a pinion member 61 that is secured to the upper end of the shaft 60 and is adapted to mesh with a suitable horizontally-movable rack member 62 ; a plurality of piston members 63 and 64 that are respectively rigidly and loosely associated with the opposite ends of the rack member 62 , and are respectively adapted to operate within cylinders 65 and 66 ; and an "on" valve and an "off" valve that are associated with the cylinders 65 and 66 , respectively.

The mechanical connection of the piston 64 with the rack member 62 is similar to the resilient lost-motion connection between the piston rods 23 and 25 of Fig. 1. The piston 64 is biased, by the unbalanced fluid-conditions already described, to the position that is shown in the drawing, wherein the piston engages a shoulder 21^b of the cylinder 66 that corresponds to the stop member 21^a of the operating mechanism OM . A suitable sleeve member 26^a is secured to the inner face of the piston 64 and incloses a suitable helical spring 28^a that is adapted to operate between the piston 64 and the end portion 23^a of the rack member 62 . Without further description, it will be understood that the general mechanical operation of the piston members 64 and 63 and the intermediate rack and pinion connection is similar to the operation of the mechanism OM that has already been set forth. In the present instance, however, the resilient lost-

motion connection between the two pistons is employed to effect a relatively rapid initial movement of the control drum PK from the "off" position that is shown in the drawing to the initial operative position a' . It will be observed that, inasmuch as the control drum occupies its "off" position, a secondary break in the circuit is provided by the contact members, thereof, a primary break being supplied by the switch LS . The advantages of such an arrangement of parts have already been explained.

Referring to Fig. 4, the auxiliary governing circuits that are shown comprise the actuating coils of the "on" and the "off" valves and of the switch LS ; the contact members of the interlock drum ID and the auxiliary contact members of the limit switch L ; and, in addition, a master controller MC^1 that is adapted to occupy a plurality of operative positions a to e , inclusive, the battery B or other suitable source of energy and a plurality of train-line conductors TL .

Assuming that it is desired to effect acceleration of the electric motor that is shown in Fig. 3, the master controller MC^1 may be actuated to its initial position a , wherein one circuit is established from one terminal of the battery B through conductor 80 , control fingers 81 and 82 which are bridged by contact segment 83 of the master controller, conductor 84 , train-line conductor 85 , conductor 86 , a junction-point 87 , where the circuit divides, one branch including conductor 88 , the actuating coil 35 of the "on" valve and conductor 93 , and the other branch including conductor 90 , the actuating coil of the switch LS and conductor 91 , whence a common circuit is completed through conductors 93 and 94 to the negative battery terminal. The "on" valve-actuating coil being thus energized, the piston 63 is rapidly moved to the right as far as the associated resilient lost-motion connection will permit, whereby the control drum PK is actuated to its initial operative position a' .

As soon as the control drum PK occupies its position a' , a main circuit is established from the trolley through conductor 70 , switch LS , conductor 71 , control fingers 72 and 73 which are bridged by the contact segment 74 of the main drum portion MD , the accelerating resistor AR , conductor 75 , armature A^1 , field winding F^1 , and the actuating coil of the limit switch L to the negative conductor ground.

By moving the master controller to its position b , a further circuit is completed from the contact segment 83 of the master controller through control finger 95 , conductor 96 , train-line conductor 96^a , conductor 97 , control finger 98 , contact segments 99 to 103 , inclusive, of the interlock drum

1D, and control finger 104, conductor 105, auxiliary contact members 106 of the limit switch L, when occupying its low-current position, and the actuating coil 38 of the 5 "off" valve to the negatively-connected conductor 89. Both coils 35 and 38 being thus simultaneously energized, the control drum PK is actuated to its position b'.

The control drum PK moves forward in 10 a step-by-step manner to be described, by reason of the arrangement of contact members of the interlock drum ID with respect to the master controller contact members, whereby the control drum is positively and 15 reliably brought to rest in the desired position. Just before the control drum reaches position b', the circuit of the coil 38 of the "off" valve is broken by the disconnection of control finger 98 and contact segment 99. To continue the operation of the control 20 drum, the master controller is moved to its position c, whereby a circuit is established from the contact segment 83 through control finger 108, conductor 109, train-line conductor 110, conductor 111, control finger 112 of the interlock drum, and thence 25 through contact segment 100 to the coil 38, as already described.

The operation just recited is repeated as 30 the master controller is actuated through its remaining operative positions, as will be understood. However, the use of such an interlock drum forms no material part of my present invention, except that it performs a certain function in connection therewith, and no further description of the operation thereof is believed to be necessary. The construction and operation of such interlock drums is fully shown and described 35 in my co-pending application, Serial No. 796,867, filed October 23, 1913.

The PK control drum is thus intermittently actuated toward its final operative position e', whereby the accelerating resistor 40 AR is gradually short-circuited to effect suitable acceleration of the motors.

If desired, the system may be automatically governed by the limit switch L after the master controller is initially moved to 50 its final operative position e, in accordance with a familiar practice which need not be described here. In such cases, it will be understood that the PK drum is initially actuated rapidly to its initial operative position a' by reason of the lost-motion connection, and subsequent drum operation is dependent upon the limit switch.

While I have shown and described my invention in connection with certain structures and control systems for illustrative purposes, it will be understood that the field of application of the invention is not so limited, and that various modifications thereof may be made without departing 60 from its spirit and scope. I desire, there-

fore, that only such limitations shall be imposed as are indicated in the appended claims.

I claim as my invention:

1. The combination with a movable member, of actuating means therefor comprising an operating cylinder, a pair of movable pistons disposed therein, means for normally producing materially different fluid pressures on said pistons to bias them to a predetermined position, means for reversing the unbalanced fluid-pressure conditions to effect normal movements of said member, and means for permitting an initial movement of one piston prior to the normal joint movement of the two pistons. 70

2. The combination with a movable member, of actuating means therefor comprising an operating cylinder, a pair of movable pistons disposed therein, means for normally producing relatively high fluid-pressure conditions on the outer face of one piston and atmospheric-pressure conditions on the outer face of the other piston, means for reversing the unbalanced fluid-pressure conditions to effect normal movements of said member and means for permitting a relatively rapid initial movement of said other piston during the reversal. 80

3. The combination with a fluid-containing cylinder and a pair of movable pistons disposed therein, of means for effecting a predetermined normal movement of said pistons, and means co-operating with said first means for effecting a relatively rapid initial movement of one of said pistons. 85

4. The combination with a movable member, of fluid-pressure-operated means normally biased by unbalanced-pressure conditions to a predetermined position, means for reversing the unbalanced action to effect normal movement of said member, and means for permitting a relatively rapid independent movement of said member before the completion of the reversal. 105

5. The combination with a movable member of an operating mechanism therefor comprising a cylinder, a plurality of piston members traveling therein, means for normally producing unbalanced-pressure conditions on the outer faces of said piston members to bias said movable members to a predetermined position, means for reversing the unbalanced action to effect normal movement of said member, and means disposed intermediate said piston members for permitting an initial relatively rapid movement of said movable member before the completion of the reversal. 115

6. The combination with a movable member, of an operating mechanism therefor, comprising a cylinder, a plurality of pistons traveling therein, a plurality of valves for normally producing unbalanced pressure conditions on the outer faces of said pistons 125

- to bias said movable member to an inoperative position, means for reversing the operation of said valves to reverse the unbalanced action and effect normal movement of 5 said member, and a resilient connection intermediate said pistons whereby an initial movement of one piston and the movable member may be effected before movement of the other piston.
- 10 7. The combination with a movable member, of an operating mechanism therefor comprising a cylinder, a plurality of loosely-connected pistons traveling therein, means for normally producing unbalanced fluid- 15 pressure conditions on the outer faces of said pistons to bias said movable member to a predetermined position, resilient means disposed intermediate said pistons and acting in a direction to assist the normal fluid- 20 pressure unbalance, means for reversing the unbalanced action to effect normal operation of said member, whereby said resilient means is rapidly compressed and predetermined initial movement of said member is 25 effected before the completion of the fluid-pressure reversal.
8. The combination with a movable member, of a fluid-containing member and an operating device disposed therein having a 30 plurality of parts acting in unison to effect normal movements of said member, and a lost-motion connection disposed intermediate said parts to permit initial independent movements thereof.
- 35 9. The combination with a movable member, of an operating device comprising a cylinder, a plurality of pistons traveling therein and adapted under normal operating conditions to act in unison, and a resilient lost- 40 motion connection disposed intermediate said pistons to permit initial independent movement thereof.
10. The combination with a movable member, of an operating mechanism therefor comprising a cylinder, a plurality of pistons traveling therein, a spring member disposed intermediate said pistons acting to bias the first piston and said movable member to a predetermined position, stopping means in 45 said cylinder, means for normally admitting fluid pressure to a certain end of the cylinder to hold the second piston against said stopping means, and means for admitting fluid-pressure to the other end of the 50 cylinder and simultaneously allowing the pressure in said certain end to be released, whereby said spring member is compressed and said movable member is rapidly actuated to a predetermined position before the 55 complete release of the fluid-pressure.
- 60 11. The combination with a movable mem-
- ber, of fluid-pressure-operated means having one movable part normally biased by unbalanced-pressure conditions to a predetermined position, and means for impressing 65 fluid-pressure upon another movable part to actuate said last named part independently of said first-named movable part.
12. The combination with a movable member, of an operating mechanism therefor 70 comprising a cylinder, a plurality of pistons traveling therein, means for normally producing unbalanced-pressure conditions on the outer faces of said pistons to bias said movable member to a predetermined position, means for initially balancing the pressures on said piston faces, and means for thereupon permitting a relatively rapid actuation of one of said pistons and of the movable member to another predetermined position 75 independently of the other piston.
13. The combination with a fluid-containing cylinder and a plurality of relatively movable pistons adapted to move therein, of 80 resilient means disposed between said pistons.
14. The combination with a fluid-containing cylinder and a plurality of mechanically associated pistons adapted to move therein, and means acting upon the pistons for permitting relative movement between said pistons. 85
15. The combination with a fluid-containing cylinder and a plurality of relatively movable pistons adapted to move therein, of 90 a coil spring interposed between said pistons.
16. The combination with a fluid-containing cylinder and a plurality of mechanically associated pistons adapted to move therein, of 95 means for permitting relative movement between said pistons, and means for limiting the movement of one of said pistons.
17. The combination with a fluid-containing cylinder and a pair of relatively movable pistons disposed therein, of a yielding mechanical connection between said pistons and a member to be actuated associated with one of said pistons. 100
18. The combination with a fluid-containing cylinder and a pair of movable pistons disposed therein, of a sleeve member associated with one of said pistons, another member associated with the other piston and projecting within said sleeve member, and 105 a coil spring disposed within said sleeve member and acting upon said other member.
- In testimony whereof, I have hereunto subscribed my name this 5th day of Feb. 1916.
